HENRY PRICE BALL, OF NEW YORK, N. Y., ASSIGNOR OF ONE-HALF TO
SAMUEL INSULL, OF CHICAGO, ILLINOIS.

TRACKER-BOARD FOR MECHANICAL MUSICAL INSTRUMENTS.

No. 837,910.

Specification of Letters Patent.

Patented Dec. 11, 1906.

Application filed August 18, 1902. Serial No. 119,987.

To all whom it may concern:

Be it known that I, HENRY PRICE BALL, a citizen of the United States, residing at New York city, county and State of New York, have invented certain new and useful Improvements in Tracker-Boards for Mechanical Musical Instruments, of which the following is a specification.

Mechanical musical instruments of the pianola class employ tracker-boards of different widths. This involves the employment of a music-sheet having a width corresponding to that of the tracker-board with which it is to be used. This condition is objectionable in that all musical compositions are not produced in rolls of different widths, and consequently it may happen that a particular composition cannot be obtained of the desired width.

20 To overcome the objections stated, I have devised a removable and adjustable tracker-board of definite width, which may be applied to the fixed tracker-board of any instrument, the object of my invention being 25 to provide means whereby music-sheets of a given width can be used on any mechanical musical instrument.

The accompanying drawings will serve to illustrate my invention.

30 Figure 1 is a transverse vertical section through a portion of a mechanical musical instrument, such as a pianola, for operating the piano and shows the removable and adjustable tracker-board in position. Fig. 2 is 35 a longitudinal section through the fixed and removable tracker-boards and frame of the instrument on the line X X of Fig. 3. Fig. 3 is a plan view of the instrument and music-sheet with the top removed.

40 In the drawings, A indicates the usual tracker-board, provided with a series of vertical air-ducts B, the air-ducts on the extreme ends of the tracker-board being at a definite distance from each other.

45 C indicates a removable and adjustable tracker-board mounted over the fixed tracker-board A and secured to it in an air-tight relation and in any suitable manner—as, for instance, by means of the spring-clamps D.

50 This tracker-board has formed in it a series of air-ducts E, which correspond as to distance and position at their lower ends with the air-ducts B in the tracker-board A, but which at their upper ends while having air-ducts of

the same diameter have the air-ducts at the 55 extreme ends at a less distance apart than is the case with the air-ducts B. The tracker-board C is made of slightly less width than the case F of the instrument or the width of the tracker-board A, which permits it to be adjusted laterally, so as to insure registering of the air-ducts B E.

In order to secure an air-tight joint between the fixed tracker-board A and the removable tracker-board C, I secure to the 65 lower surface of the removable tracker-board a cushion, of felt, rubber, or other compressible material G, which covers the whole lower surface, except the part occupied by the ducts E.

H represents the usual perforated music-sheet, adapted to be moved over the tracker-board C and having the perforations I. This paper is unwound from roller J onto roller K. The roller K may be the usual take-up roller 75 of the instrument. The roller J, on the other hand, commonly corresponds in width with the music-sheet and is commercially sold with it.

The roller J is provided with nipples L M; 80 but as this roller is less in width than the roller designed to be used in an instrument having a fixed tracker-board of the width of A it is necessary to provide supplemental nipples N O.

To guide the music-sheet over the removable and adjustable tracker-board in order that the perforations in a music-sheet shall register accurately with the air-ducts E in the tracker-board C, I provide the adjustable 90 guides P.

In the drawings I have shown a removable tracker-board as adapted for use on an instrument having a relatively wider fixed tracker-board. Manifestly the removable tracker-board could be wider than the fixed tracker-board of the instrument with which it is to be used. It is my intention to provide tracker-boards having a definite width at the top and any desired width at the bottom, so 100 that the tracker-board may be adapted for any instrument.

Having thus described my invention, I claim—

1. In combination with a tracker-board of 105 a mechanical musical instrument having definitely-spaced air-ducts, a second removable tracker-board of different width having its

air-ducts differently spaced from those of the first-named tracker-board and arranged to co-operate therewith.

2. In combination with a tracker-board of 5 a mechanical musical instrument, a second removable tracker-board provided with air-ducts which register with those of the first-named tracker-board, said air-ducts differently spaced apart at their orifices and outlets.

3. In combination with a tracker-board of 15 a mechanical musical instrument having a series of air-ducts of definite distance between centers, of a removable tracker-board having air-ducts whose inlet-orifices differ as to distance between centers from the inlet-orifice of the air-ducts of the first-named tracker-board.

4. In combination with the tracker-board 20 of a mechanical musical instrument having a series of air-ducts, a music-roll whose perforations do not register with the air-ducts of the tracker-board, and means interposed between the two, whereby the perforations in 25 said music-roll may be brought into operative relation with the air-ducts of the tracker-board.

5. In a mechanical musical instrument and in combination with a fixed tracker-board of 30 definite width, a removable registering tracker-board of less width.

6. A mechanical musical instrument having a fixed tracker-board with air-ducts a 35 definite distance apart, and a supplemental tracker-board having air-ducts at a definite but different distance apart.

7. In an automatic playing attachment for musical instruments, the combination with the permanent tracker-bar of a detachable

tracker-bar, with perforations adapted to 40 register with the perforations in said permanent bar and to register with perforations in a music-sheet other than that for which the said permanent tracker-bar is constructed.

8. In combination with the tracker-board 45 of a mechanical musical instrument, a second superposed removable tracker-board having its central air-duct vertical and the ducts on each side thereof disposed at varying angles.

9. A mechanical musical instrument provided with two tracker-boards, one fixed to the instrument and the other removably secured in a fixed relation to the first-named tracker-board, the said tracker-boards having the upper ends of their air-ducts differently spaced between centers, and with the 50 lower ends of the ducts of the removable tracker-board spaced to co-operate with the upper ends of the ducts of the fixed tracker-board.

10. In combination with the tracker-board of a mechanical musical instrument, a second superposed removable tracker-board having the upper ends of its air-ducts differently spaced between centers from those of the 55 first tracker-board.

11. In combination with a tracker-board of a mechanical musical instrument having definitely-spaced air-ducts, a second superposed removable tracker-board having the 60 upper ends of its air-ducts differently spaced from those of the first-named tracker-board.

In testimony whereof I affix my signature in the presence of two witnesses.

HENRY PRICE BALL.
